US00D867332S

(12) **United States Design Patent** (10) Patent No.: **US D867,332 S**
 (45) Date of Patent: **** Nov. 19, 2019**

(54) **MOBILE DEVICE CHARGING CRADLE
WITH SPEAKERS**

(71) Applicant: **Shenzhen Tianyuwei Science and
Technology Co., Ltd.**, Shenzhen (CN)

(72) Inventor: **Hui Xiao**, Langao (CN)

(73) Assignee: **Shenzhen Tianyuwei Science and
Technology Co., Ltd.** (CN)

(**) Term: **15 Years**

(21) Appl. No.: **29/636,176**

(22) Filed: **Feb. 6, 2018**

(51) LOC (12) Cl. **14-03**

(52) U.S. Cl.

USPC **D14/209.1**; D13/108

Primary Examiner — Marie D. Fast Horse

(57) **CLAIM**

The ornamental design for a mobile device charging cradle with speakers, as shown and described.

DESCRIPTION

FIG. 1 is a front view of the mobile device charging cradle with speakers showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is another perspective view thereof, shown in use with unclaimed environment.

The broken lines in FIG. 8 depict environmental subject matter only and form no part of the claimed design.

1 Claim, 7 Drawing Sheets
